(57) CLAIM

The ornamental design for a picture frame for birth memories as shown and described.

DESCRIPTION

FIG. 1 is a perspective view of a picture frame for birth memories showing my new design;

FIG. 2 is a front view of thereof;

FIG. 3 is a rear view of thereof;

FIG. 4 is a top view of thereof;

FIG. 5 is a bottom view of thereof;

FIG. 6 is a right side view of thereof; and,

FIG. 7 is a left side view of thereof.

The broken lines in the figures are for the purpose of illustrating portions of the picture frame for birth memories, which form no part of the claimed design.
